UNITED STATES PATENT OFFICE

PAUL BUHRLE, OF BRONX, NEW YORK

DESIGN FOR A CLOCK CASE

Application filed August 26, 1932. Serial No. 44,699. Term of patent 3½ years.

To all whom it may concern:

Be it known that I, PAUL BUHRLE, a citizen of the United States, residing at Bronx, in the county of Bronx and State of New York, have invented a new, original, and ornamental Design for a Clock Case, of which the following is a specification, reference being had to the accompanying drawing, forming part thereof.

Fig. 1 is a front view of a clock case, showing my new design.

Fig. 2 is a side view thereof.

The ornamentation on the lower part of the frame on the opposite side and rear of the case is the same as shown.

I claim:

The ornamental design for a clock case, as shown and described.

PAUL BUHRLE.
